Primary Examiner — Jennifer L Watkins

(57) **CLAIM**

The ornamental design for a pair of safety boots, as shown and described.

DESCRIPTION

1.-4. Pair of safety boots

Compliant safety boot with compliant high visibility and retro reflective materials.

1.1 is a front perspective view of a pair of safety boots showing our new design;

1.2 is a rear view thereof;

1.3 is a side view thereof;

1.4 is another perspective view thereof;

2.1 is a front perspective view of a second embodiment of the pair of safety boots;

2.2 is a rear view thereof;

2.3 is another perspective view thereof;

2.4 is a side view thereof;

3.1 is a front perspective view of a third embodiment of the pair of safety boots;

3.2 is a rear view thereof;

3.3 is a side view thereof;

3.4 is another perspective view thereof;

4.1 is a front perspective view of a fourth embodiment of the pair of safety boots;

4.2 is a rear view thereof;

4.3 is a side view thereof; and

4.4 is another perspective view thereof.
